CLAIM

The ornamental design for a monitor stand, as shown and described.

DESCRIPTION

FIG. 1 is a perspective view of a monitor stand showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of an indicated portion of FIG. 1; and,

FIG. 9 is an enlarged view of an indicated portion of FIG. 1.

The broken line portions of the monitor stand in FIGS. 1-9 represent unclaimed portions of the claimed design and form no part thereof. The dot-dash broken lines in FIGS. 1-3 and 8-9 represent unclaimed boundary lines and form no part of the claimed design
